Des. 192,903
Patented May 22, 1962

192,903

HAIR CURLER

Henri Light, 2467 Ravenswood, Evansville, Ind.

Filed Oct. 18, 1960, Ser. No. 62,523

Term of patent 14 years

(Cl. D86—10)

FIG. 1

FIG. 2

FIG. 3

FIG. 1 shows an elevational view of a hair curler showing my new design.

FIG. 2 is a top plan view thereof.

FIG. 3 is a cross-sectional view taken along line 3—3 of FIG. 2 and looking in the direction of the arrows.

I claim:

The ornamental design for a hair curler, as shown.
